Specification of Letters Patent.

Patented Jan. 23, 1912.

Application filed July 22, 1901, Serial No. 69,204. Renewed June 16, 1911. Serial No. 633,592.

To all whom it may concern:

Be it known that I, EDWARD P. BAIRD, a resident of Chicago, in the county of Cook and State of Illinois, have invented certain new and useful Improvements in Telephone Toll Apparatus, of which the following is a full, clear, and exact description.

The present invention relates to apparatus employed to collect tolls in payment of telephone-service, and designs to provide improved mechanism which is simple in construction, and efficient in operation.

The invention consists in the several novel features hereinafter set forth and more particularly defined by claims at the conclusion hereof.

In the drawings: Figure 1 is a view in central vertical section of a toll-receiver embodying the preferred form of the invention. Fig. 2 is a view in side elevation, the case being shown in section. Fig. 3 is a plan view, parts being omitted and the case being shown in section. Fig. 4 is a view in horizontal section taken on line 4—4 of Fig.

25 1. Fig. 5 is a view in vertical section taken on line 5—5 of Fig. 2. Fig. 6 is a detail view of the latch shifter. Fig. 7 is a diagrammatic view of a telephone-system and cord loop of a central exchange having the 30 improved toll-receiver connected therewith.

The toll-receiver (shown more fully in Figs. 1—5) is located at the subscriber's station and comprises a suitable inclosing case 6, which is provided with a coin-receiving slot 8, a cup 9 for catching the refunded coins, and a coin-receptacle 10, secured in the case by a lock 11.

The operating mechanism of the toll-receiver is sustained in relative position by a 40 frame comprising sides 12 and 13 secured together and to the case in any suitable and convenient manner. A coin-carrier A is pivotally sustained by and secured to swing with, a shaft 14 journaled in the frame 45 sides and having a polygonal portion extending through a correspondingly-shaped sleeve 15 secured in wings 16 of the coin-carrier. The carrier comprises suitable walls between which a coin-guide or channel 50 17 is formed. The front or upper end of the coin-channel 17 is located immediately beneath coin-receiving slot 8 and into said channel deposited coins will fall. A stop 55 18, located adjacent the edge of channel 17, holds a deposited coin of proper size ad-

jacent the upper or front end of the carrier. The bottom or lower wall of coin-channel 17 is notched or slotted as at 19 to expose the edge-portion of a coin held in the carrier, and to permit the coin to engage and shift 60 the mechanism hereinafter described, when the carrier with a coin therein is shifted. Shaft 14 is projected through one of the side-walls of the inclosing case, and has secured to its projecting-terminal, an operating-arm or crank 20, whereby the shaft and coin-carrier may be manually shifted. A spring 21 holds the carrier in normal position, and restores the carrier after operation. A stop 22 restricts the downward movement 70 of the carrier. Wings 16 on the coin-carrier obstruct the coin-receiving slot 8 while the carrier is out of normal position and prevent a coin from being deposited into the receiver, except when the coin-channel 17 75 is immediately beneath coin-receiving slot 8 and in position to receive a deposited coin. Coin-channel 17 is extended entirely through the carrier, so a coin insufficient in diameter to engage stop 18 will pass out of the carrier 80 at its lower end.

An arm B sustained by a shaft 28 journaled in sides 12 and 13 of the frame, extends normally into the path of movement of a coin in the carrier. Arm B is engaged and shifted by a coin in the carrier, during the manually-imparted oscillatory shift of the carrier. At one side of the frame, a switch-arm C formed of non-conducting material, is secured to shaft 28 and is arranged in position to engage a contact spring 29 and is adapted to shift said spring into electrical connection with a contact-spring 31. Arm B is yieldingly held in normal position against a cross-rod 30 and is restored to such position by a spring 31'. Contacts 29 and 31 are normally insulated from each other and are secured to a block 38 of non-conducting material, in suitable manner. Said contacts 29 and 31 are connected with 95 conductor-wires 36 and 37 leading respectively to ground and to a branch-wire of the telephone line. Arm B is provided with a hook 35 adapted to be engaged by a latch G having a terminal g¹⁰ whereby the arm will be held in shifted position, until released by mechanism hereinafter described. A dog 39 provided with ratchet-teeth is pivotally sustained by cross-rod 30, is arranged 100 in the path of movement of a coin in carrier 105 110

A, engages the edge or exposed portion of the coin, and prevents retraction of the coin and carrier, and repeated operation of arm B by the same coin. Said dog is held in proper normal position against a stop 40 and restored thereto by a spring 41. In operation, the coin successively engages the teeth of the dog, and the carrier is held against retraction until the coin has been 10 discharged from the carrier.

When a coin is shifted by the carrier, and the coin has passed beneath arm B and dog 39, the coin will be discharged from the carrier and will fall into a movable coin-distributer E. Beneath the coin-distributer a stop 44 is formed whereon the coin, after discharge from the carrier, will rest. Thus it will be seen that each deposited coin of proper size will be shifted by the carrier, 20 to cause the shift of a switch, and then discharged into the movable distributer E and will be held therein (until displaced by mechanism hereinafter described) by stop 44. In back of stop 44 guides 45 are provided to direct coins, when the coin-distributer is shifted backwardly, into coin-receptacle 10, and in front of said stop a guide or run-way 26 is formed, to direct coins from stop 44 (when the distributer is moved forwardly) through an exit opening 27 and into cap 9 at the outside of the case.

The movable distributer E is sustained by a plunger 49 mounted in manner free to slide in laterally projecting lugs 51 of a bracket 50 secured to side 12 of the frame. The distributer is positioned normally above stop 44 by springs 46 and 47, is free to be moved both forwardly and rearwardly of the normal position. Spring 46 restores the distributer to normal position after forward shift thereof, to refund a coin, and spring 47 restores the distributer to normal position after backward shift thereof to displace a coin into the coin receptacle. Plunger 49 is provided with a handle 52 at its forward terminal, and thereby the plunger and distributer can be manually shifted either forwardly or rearwardly. Plunger 49 is also provided with a stud or lug 53 adapted to travel in a cam-slot having inclined edges g and g' of a latch-shifter G', which has its upper end pivotally secured to latch G, and has its lower end guided between lugs 51 of bracket 50. Stud 53 is arranged to engage cam-edge g' and lower shifter G' and latch G when the plunger 49 is moved forwardly, and to engage cam-edge g and likewise lower shifter G' and latch G when the plunger is moved backwardly. Latch G is pivotally-sustained by a cross-rod g⁶ and held in and restored to normal position by a spring g⁷. Thus it will be seen, that upon shift of the plunger in either direction the latch will be withdrawn from engagement 60 with hook 35 of arm B and the said arm will

then be free to be restored to normal position by spring 31. Arm B, by means of switch C and contacts 29 and 31, controls the operation of the "line-signal" at the central office. The latch G serves to retain 70 the switch in operative position and until the distributer is shifted to displace the coin therein. This mechanism serves as means whereby the "line-signal" will be coin-controlled, and whereby the displacement of the 75 coin will be effected by manual shift.

A device for producing an audible signal is provided to notify the operator at the central office that the distributer has been shifted to deposit the coin into the coin-receptacle. Such signal is usually conducted through the back-board of a telephone set, and the transmitter over the telephone-line. The mechanism for actuating said signal comprises a swinging dog m pivotally sustained, as at m', by the distributer and carried thereby, and so arranged that a coin in the distributer will shift said dog, into position to engage a signal-actuating lever m² secured to a sleeve m³, which is pivotally sustained by a stud m⁴ projecting from side 13 of the frame. Side 13 of the frame is provided with an opening a⁸ wherethrough the dog m can project to engage lever m². A pawl m⁵ pivotally secured to lever m² 95 is adapted to engage and bend the free terminal of a flexible strip M, which, when suddenly released from engagement with said pawl, will vibrate and inherently, produce an audible signal. Pawl m⁵ is provided with an abutment m⁶ which engages lever m² and is held against said lever and by a spring m⁷ during the backward travel of said lever, so the pawl will move with the lever but on forward shift of the lever, 100 the pawl will travel freely over the flexible strip M, without effecting the vibration of said strip. Dog m is provided with a stop m⁸ for limiting the inward movement thereof and positioning the dog normally in the 110 path of a coin falling into the distributer. Obviously the audible signal device will be actuated only when a coin is held in the distributer and the distributer is shifted backwardly to displace a coin into the coin-receptacle. Such mechanism, therefore, serves as coin-controlled means for actuating the 115 audible signal when the distributer is shifted to deposit a coin beyond control of the depositor, and notify the operator at the 120 central office that a deposited coin has been displaced from the distributer to the coin-receptacle.

A register T is provided to indicate the number of coins deposited into the coin-receptacle. Said register is of usual construction and it has not been deemed necessary to illustrate it in detail. The case t of the register is secured to lugs a of the case A, and in such position the front of the register is 130

exposed through a sight-opening a' in the inclosing case A. The register comprises a shaft t' whereby the counting mechanism is advanced in step-by-step fashion, and to shaft t' an operating-arm t^2 is secured, which has a limited oscillatory movement necessary to advance the counting mechanism. A pitman t^3 has one end pivotally secured to the distal end of arm t^2 and has its other end pivotally secured to a flexible crank-arm t^5 secured to sleeve m^4 which carries and moves with the operating-arm of the device for producing an audible signal. Crank-arm t^5 is preferably made slightly flexible so the necessary stroke may be imparted to the lever m^2 to insure the operation of strip M without being restricted to the predetermined limited travel of register-arm t^2 . Furthermore, the difference in the thickness of coins will cause the shift of lever m^2 to vary slightly, therefore an excess of movement is imparted to lever m^2 and the flexible-crank-arm permits such differential movement of lever m^2 while always imparting a uniform travel to the register-arm t^2 . A spring V restores lever m^2 , crank-arm t^5 and operating-arm t^2 to normal position after shift of such parts.

Referring more particularly to Fig. 7, H designates a subscriber's station, I a switch-board located in a central exchange K, and J is a connecting line comprising branches 55 and 56. These branches terminate respectively in line-springs i and i' of switch-board I at the central exchange, and at the subscriber's station, in the usual parts, including a transmitter, induction-coils, receiver, signal-bell and switch-hook, connected together in usual manner, as well understood in the art. The switch-board shown is of the type commonly known as a "relay-board". A line-relay 58 is associated with each subscriber's line and is included in a signal circuit comprising branch 55 of the line, switch 77 and wires 77 and 77^b extending to battery 75 and to ground at 82. When energized, the line-relay causes the actuation of a visual signal 79 (such as a lamp) in a local circuit. A cut-off relay 59 included in a circuit which extends from ground at 82, by conductor 81 and terminating in a test-ring, excludes the line-relay and visual signal or indicator from the signal circuit when the operator inserts a plug into the spring-jack.

L denotes a cord-circuit including plugs 61 and 62, a battery 63 and other usual parts and signals at the central exchange. At the subscriber's station, a branch-wire 37 connects branch 55 of the telephone with contact 31 of the normally open coin-controlled switch C, and a wire 36 connects contact 29 of said switch with ground as at 90.

The operation will be as follows: To signal the central exchange, the subscriber in-

serts a coin of proper denomination and size through coin-receiving slot 8 (see Fig. 1) into coin-carrier A. The depositor then shifts operating-arm 20 forwardly, and such movement will positively shift the coin downward, so the coin will engage dog 39 and retraction of the coin will be prevented thereby. The coin will also engage and shift arm B until hook 35 thereof passes beyond the bent terminal of latch G, when the arm will be held in such position. While arm B is thus held by latch G, switch-arm C will hold the contacts 29 and 31 into electrical connection, and with the parts in such position, the line-relay will immediately notify the central operator of the deposit of a coin into the toll-receiver, because current will flow from battery 75 (which is grounded at 82), over conductor 77, through line-relay 58 (energizing said relay and closing the local signal circuit wherein visual signal 79 is located), thence through switch 77^a, over branch 55 of the telephone-line, thence by conductor 37, contact springs 31 and 29, and conductor 36 to ground at 90. Visual signal 79 will thus notify the central operator that a connection is desired and that a coin has been deposited. Such signal continues until the central operator responds by inserting a plug of the cord-circuit into the spring-jack of the switchboard I. When the central operator inserts a plug into the spring-jack, the cut-out relay will be energized, attract its armature and break the signal circuit of lamp 79 as well understood in the art. The central operator can then communicate with the depositor, and ascertain the connection desired. After shift of arm B, the coin in carrier A will be discharged into distributor E, and will shift dog m into position to cause the operation of the device for producing an audible signal, and register T. After having ascertained the connection desired by the depositor, the central operator will ascertain in usual manner whether or not the desired connection can be obtained. If the desired connection can be obtained, the operator directs the depositor to push handle 51 inwardly. The inward shift of the plunger will shift the distributor and the coin therein, to cause dog m to engage lever m^2 , thus shifting pawl m^5 to actuate the flexible strip M to produce an audible signal which will be conducted over the telephone-line to the operator. Simultaneously, the coin in the distributor will be shifted backwardly of stop 44 so it will fall into receptacle 10. The audible signal will notify the central operator that the coin has been removed from the distributor and into the coin-receptacle. If the audible signal is not heard, the central operator will know that the coin has been removed, or that the line-signal has been operated by fraudulent means, and will not

give the connection desired. If the audible signal is heard by the central operator, the desired connection will be given. When the plunger 49 is shifted backwardly, stud 53 will engage cam-edge g of the latch-shifter, and thus withdraw the latch from engagement with arm B, to permit said arm to be restored to normal position by spring 31'. The release of arm B will shift switch C 10 to disconnect contacts 29 and 31, thus breaking the signal circuit at such point, and rendering the line-relay inoperative until another coin has been deposited. During each backward shift of the distributor with a coin 15 therein, the register T will be operated by crank-arm t^5 (which is secured to move in unison with lever m^2), pitman t^3 and operating-arm t^2 . A true record will thus be kept of the number of coins deposited in the 20 coin-receptacle, so the collector can ascertain whether or not any of the coins have been fraudulently removed. If the connection desired by the depositor cannot be made, the central operator will direct the depositor to pull the handle 52 forwardly. The forward shift of the plunger will cause stud 53 to engage cam-edge g' to withdraw latch G from engagement with arm B and release said arm to break the signal circuit at contacts 29 and 31, and to render the line-relay 25 inoperative. The forward shift of the distributor will cause the coin therein to pass forwardly of stop 44 so it will fall through exit 27 and into cup 9 and thus refund the 30 coin to the depositor. It will be seen that when a coin is refunded, the audible signal and register are not operated.

The invention provides an improved toll-apparatus which is simple in construction 40 and which is efficient in operation.

While the toll-receiver is shown as adapted to receive coins, it is obvious that any toll-representing check or token can be used, and the term "coin" as used herein is to be understood as including any toll-representing 45 check or token.

The invention is not to be understood as restricted to the details shown and described, but may be varied without departing from 50 the spirit of the invention, and the several novel features may be employed severally without its adoption in entirety.

Having thus described my invention what I claim as new and desire to secure by Letters Patent is:—

1. In a toll-apparatus for telephones, the combination with a coin-controlled switch for controlling passage of current over an electrical circuit, of means whereby said 60 switch will be locked in shifted position, coin-distributor-mechanism, means whereby said distributor-mechanism can be operated by the depositor, and means whereby said switch-locking-means will be operated to release said switch when the means where-

by the depositor shifts the distributor-mechanism is shifted to place a coin beyond control of the depositor.

2. In a toll-apparatus for telephones, the combination with a coin-controlled-switch 70 for controlling passage of current over an electrical circuit, of means whereby said switch will be locked in shifted position, coin-distributor-mechanism, means whereby said distributor-mechanism can be operated by the depositor, and means whereby said switch-locking-means will be operated to release said switch when the means whereby the depositor operates the distributor-mechanism is shifted to place a coin beyond control of the depositor or to refund a coin. 75

3. In toll apparatus for telephones, the combination with a signal circuit and a line-signal at the central exchange, of a switch at the sub-station for controlling the 80 operation of said line-signal, means whereby said switch will be shifted into position to cause the operation of the line-signal when a coin is deposited, means for holding said switch in position to cause the operation of the line-signal, coin distributor mechanism operable by the depositor to place a coin beyond his control, and means whereby the switch holding means will be operated to release the switch when the distributor 85 mechanism is operated. 90

4. In toll apparatus for telephones, the combination with a signal-circuit and a line-signal at the central exchange, of a line-signal-switch at the sub-station for controlling the operation of said line-signal, coin-controlled mechanism for shifting said switch, a latch for holding said switch in 100 position to cause the actuation of the line-signal, and means whereby the release of said switch may be manually effected by the depositor. 105

5. In toll apparatus for telephones, the combination with a signal-circuit and a line-signal at the central exchange, of a line-signal-switch at the sub-station for controlling the operation of said line-signal, mechanism whereby a coin can be positively shifted to set said switch into position to cause the actuation of said line-signal, means comprising a latch for holding the switch in such position, and means whereby the release of said switch may be manually effected by the depositor. 110 115

6. In toll apparatus for telephones, the combination with a signal-circuit and a line-signal at the central exchange, of a line-signal switch at the sub-station, a swinging carrier having a pocket for holding a coin and whereby a coin will be positively shifted 120 to shift said switch to effect the operation of the line-signal, means comprising a latch for holding the switch in such position, and means whereby the release of said switch 125 can be manually effected by the depositor. 130

7. In toll apparatus for telephones, the combination with a signal-circuit and a line-signal at the central exchange, of a line-signal switch at the sub-station for controlling the actuation of said line-signal, mechanism for positively shifting a coin to shift said switch to effect the actuation of the line-signal, a switch-arm located in the path of movement of a coin held in the 10 coin-shifting mechanism, a latch for holding said switch-arm in such position, and means whereby the switch can be manually released by the depositor.

8. In toll apparatus for telephones, the combination with a signal-circuit and a line-signal at the central exchange of a line-signal switch at the sub-station for controlling the operation of the line-signal, means for shifting a coin to shift said switch to effect the operation of the line-signal, a latch for holding said switch in such position, and a coin-distributer connected to said latch so that the line-signal switch will be released when the distributer 25 is operated.

9. In toll apparatus for telephones, the combination with a signal-circuit and a line-signal at the central exchange, of a line-signal switch at the sub-station for controlling the operation of the line-signal, means for shifting a coin to shift said switch to effect the operation of the line-signal, a latch for holding said switch in such position, a coin-distributer connected to the 30 latch so that the switch will be released when the distributer-mechanism is operated, and means whereby the distributer can be operated by the depositor.

10. In toll apparatus for telephones, the combination with a signal-circuit and a line-signal at the central exchange, of a line-signal switch at the sub-station for controlling the operation of the line-signal, means for shifting a coin to shift said switch to 40 effect the operation of the line-signal, a latch for holding said switch in such position, a coin-distributer, and means whereby said latch will be released when a coin is placed beyond control of the depositor or 45 refunded.

11. A toll apparatus for telephones, comprising the combination with distributing mechanism whereby a coin may be displaced into the coin-receptacle or returned to the depositor, of a sound-yielding body, a lever for causing the actuation of said body, a pawl secured to move in one direction with said lever and free to move independently in reverse direction, and means whereby said lever will be shifted only when the distributing mechanism is operated to displace a coin into the coin-receptacle.

12. The combination with a telephone-line and a signal circuit including a line-signal at the central office, and a coin-controlled

switch at the subscriber's station, of means for shifting said switch, means for holding said switch in shifted position, distributor mechanism whereby a deposited coin may be displaced into the coin-receptacle, or returned to the depositor, a device for producing an audible signal, means whereby the distributor mechanism will cause the release of the switch, and means whereby the shift of said mechanism in one direction will 70 cause the actuation of said device. 75

13. The combination with a telephone-line and a signal circuit including a line-signal at the central office, and a coin-controlled switch at the subscriber's station, of means for shifting said switch, means for holding said switch in shifted position, manually-controlled distributor mechanism whereby a deposited coin may be displaced into the coin-receptacle, or returned to the depositor, 80 a device for producing an audible signal, means whereby the distributor mechanism will cause the release of switch, and means whereby the shift of said mechanism in one direction will cause the actuation of said 85 device. 90

14. The combination with a telephone-line and a signal circuit including a line-signal at the central office, and a coin-controlled switch at the subscriber's station, of means for shifting said switch, means for holding said switch in shifted position, distributor mechanism whereby a deposited coin may be displaced into the coin-receptacle, or returned to the depositor, a device for producing an audible signal, means whereby the distributor mechanism will cause the release of the switch when shifted either to displace a coin into the receptacle or return a coin, and means whereby the shift of said mechanism will cause the actuation of said device, when a coin is displaced into the receptacle. 95 100

15. A toll apparatus for telephones, comprising the combination with a distributing mechanism whereby a coin may be displaced into a coin-receptacle, or returned to the depositor, of a register and coin-actuated means whereby said register will be operated only when a coin is displaced into the coin-receptacle. 110 115

16. A toll apparatus for telephones, comprising the combination with a distributing mechanism, whereby a coin may be displaced into a coin-receptacle or returned to the depositor, of a register and means whereby said register will be operated only when a coin is displaced into the coin-receptacle, said means including a flexible arm. 120

17. A toll apparatus for telephones, comprising the combination of distributing mechanism whereby a coin may be displaced into the coin-receptacle or returned to the depositor, of a coin-controlled device for producing an audible signal, a register, and 125 130

coin-actuated means whereby said device will be actuated and said register will be operated by each operation of the distributing mechanism to displace a coin into the receptacle.

18. A toll apparatus for telephones, comprising the combination of manually-operated distributing mechanism, whereby a coin may be displaced into the coin-receptacle or returned to the depositor, of a device for producing an audible signal, a register, and means whereby said device will be actuated and said register will be operated by each operation of the distributing mechanism to displace a coin into the receptacle, said means including a coin-controlled dog movable with the distributing mechanism.

19. A toll apparatus for telephones, comprising the combination of distributing

mechanism whereby a coin may be displaced ²⁶ into the coin-receptacle or returned to the depositor, of a device for producing an audible signal, a register, and means whereby said device will be actuated and said register will be operated by each operation of the distributing mechanism to displace a coin into the receptacle, said means including a coin-controlled dog shifted by the distributing mechanism, a lever for effecting the actuation of said device, and a yielding connection ²⁵ between said lever and said register, and which permits a differential shift of the register. ³⁰
